UNITED STATES PATENT OFFICE.

HALLIE LA BEAUD, OF NEW YORK, N. Y.

SHOWER SHAWL.

Application filed March 31, 1926. Serial No. 88,801.

The present invention is concerned with the provision of a device which I have elected to term a shower shawl, and which is in the nature of a cheap paper shawl or cape adapted to be donned in an emergency to protect the wearer's clothing from being injured by rain.

A preferred embodiment of the invention provides a device of this character including a body encircling portion adapted to be thrown about the shoulders of a wearer and a hood portion forming a continuation of the body encircling portion for protecting a wearer's hat.

Preferably the article is made of some extremely cheap material such as water proofed paper, and is so arranged, that it may be folded and stored in a minimum amount of space.

Objects of the invention are to provide a device of this character which will be self adjusting to accommodate various sized users, which may be quickly donned, which will afford effective temporary protection from the rain, and which may be manufactured with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a perspective view illustrating the manner of use of a shower shawl embodying the present invention.

Fig. 2 is a plan view of the blank from which the shawl is folded.

Fig. 3 is a plan view showing the blank partially folded.

Fig. 4 is a view of the completely folded blank.

Fig. 5 is an enlarged transverse sectional view on the line 5—5 of Fig. 4.

As suggested above the device of the present invention is preferably made of some cheap material, such as ordinary water proofed paper, and in Fig. 1 it will be noted that it includes a body encircling element in the nature of a shawl or cape, and a hood which extends over the wearer's head. The device is preferably so constructed that the hood or top of the article is formed of a

plurality of thicknesses of paper, so that the rain cannot beat through. The device may be best understood by considering the blank from which it is folded, and the manner of folding the blank to produce the finished shawl.

As seen in Fig. 2 the blank 10 comprises a substantially rectangular sheet of suitable material such as paper. The width of the blank (shown as its longer dimension), will be substantially uniform in all cases, and the length of the blank (shown as its shorter dimension) may be varied in accordance with the particular length of cape desired. Adjacent each side edge of the blank there is provided a longitudinal fold line 11, so that the blank edges 12 may be turned inwardly to reinforce the edges of the cape. The blank includes a back section 13, front sections 14 and a top or hood section 29 which is cooperatively defined by the upper ends of both the back sections and the front sections. Between the front sections 14 and the back section 13 a plurality of longitudinal fold lines 15 are formed, these fold lines when the blank is folded, serving to produce a series of pleats 16 best seen in Figs. 3 and 5. The pleats render the cape or shawl adjustable as to size and are readily expandable or contractible to accommodate the device to a wearer.

The points which I have designated as A on the blank, constitute the upper outer corners of the front sections when the blank is completely folded. These points are disposed upon the outermost pleat folding line 15 at points near the upper ends thereof. The points A are connected to the fold lines 11 by a series of diverging fold lines 17, 18 and 19. Fold lines 17 extend from the point A to the junction of the fold line 11 with the upper edge of the blank. Fold line 18 extends slightly downwardly from point A to the fold line 11, and fold line 19 is sharply inclined terminating near the lower end of the fold line 11.

Between the two innermost pleat fold lines 15 there is a transverse fold line 20 adapted to register with fold lines 17 in the completed article. All of the material of the blank above the fold lines 17 and 20 constitutes the top or hood of the shower shawl and affords a multiply hood, as will be later described.

The first operation of folding the blank 110

consists in producing the pleats 16 by folding alternately in opposite directions on the pleat fold lines 15. The edges 12 of the blank are then turned inwardly on the line 11, and the front sections 14 of the blank folded inwardly over the back section on the outer pleat folding line 15. In Fig. 3 I have shown one of the front sections so folded, and have also illustrated 10 the next folding operation which consists in breaking or folding front sections 14 simultaneously on the three fold lines 17, 18 and 19. Front section 14 is folded outwardly on the line 17. When the other front section 14 has been similarly folded, the two fold lines 17 will register with fold line 20.

The edges of the front sections 14 which are disposed between the fold lines 18 and 20 17 constitute the forward edge 21 of the hood when the device is completely folded. Having folded the two front sections inwardly and broken them on the fold lines 17, 18 and 19, as above described, the next 25 operation consists in folding the top section 22 downwardly on the line 20. Before this is accomplished however, I preferably fold the top section rearwardly on the line 23, then forwardly on the line 24 to provide a 30 reinforced doubly folded vizor portion 25 as seen in Fig. 4. This vizor portion aligns with the edge 21 of the hood, and is secured thereto by the use of a pin or rivet 26. In Figs. 2 and 3 I have shown the rivet holes 35 27 in the various blank sections, all of these rivet holes being aligned with each other when the blank is completely folded.

With the blank in the completely folded position of Fig. 4, it will be noted that it 40 lies substantially flat. When however, the shawl is donned, the front sections are folded outwardly on the lines 19 to define a pair of forwardly projecting wing portions 28 which support the forward edge of the 45 hood 29 and which are integrally connected to the side edges of the hood.

The wing portions 28 define with the forward edge of the hood a substantially triangular opening 30 exposing the face of 50 the wearer. The two edge portions 12 may be connected together by the use of a tape 31 secured in eyelets 32 in the reinforced edges, or the two edges may be detachably secured together in any approved manner, 55 so that the arms of the user are concealed within, and protected by the shawl or cape.

Obviously the device may be folded in other ways without departing from the invention, and various slight changes and alterations might be made in the general form 60 and arrangement of parts described without departing from the invention. Hence I do not wish to limit myself to the details set forth, but shall consider myself at liberty 65 to make such changes and alterations as

fairly fall within the spirit and scope of the appended claims.

I claim:

1. A paper shower shawl folded from an approximately rectangular blank, said blank being provided with transverse fold lines defining a body-encircling element formed of a back section, two front sections and a series of pleats between the back section and the two front sections, the intermediate portion of the blank being formed with a transverse fold line defining a forwardly folding hood top portion integral with the top of the back section, and adapted to rest on a wearer's head, the upper portions of the front sections being folded inwardly on diagonal fold lines and connected to the forward edge of the hood top, the diagonally folded upper ends of said front sections defining flaring side wing portions integral with the hood top. 75 80 85

2. A paper shower shawl folded from an approximately rectangular blank, said blank being provided with transverse fold lines defining a body-encircling element formed of a back section, two front sections and a series of pleats between the back section and the two front sections, the intermediate portion of the blank being formed with a transverse fold line defining a forwardly folding hood top portion integral with the top of the back section, and adapted to rest on a wearer's head, the upper portions of the front sections being folded inwardly on diagonal fold lines and connected to the forward edge of the hood top, the diagonally folded upper ends of said front sections defining flaring side wing portions integral with the hood top, the upper ends of the wing portions extending beneath the hood top to define a multiply structure at the top of the hood. 90 95 100 105

3. A paper shower shawl folded from an approximately rectangular blank, said blank being provided with transverse fold lines defining a body-encircling element formed of a back section, two front sections and a series of pleats between the back section and the two front sections, the intermediate portion of the blank being formed with a transverse fold line defining a forwardly folding hood top portion integral with the top of the back section, and adapted to rest on a wearer's head, the upper portions of the front sections being folded inwardly on diagonal fold lines and connected to the forward edge of the hood top, the diagonally folded upper ends of said front sections defining flaring side wing portions integral with the hood top, the forward edge of the hood top being folded upon itself to define a stiffening vizor and the connections between the hood top and the side wings being through said vizor. 110 115 120 125
